UNITED STATES PATENT OFFICE.

CLARENCE H. POND, OF WINCHESTER, MASSACHUSETTS, ASSIGNOR TO IVERS & POND PIANO COMPANY, OF BOSTON, MASSACHUSETTS, A CORPORATION OF MASSACHUSETTS.

PIANO BENCH.

Application filed October 29, 1927. Serial No. 229,740.

My invention has for its object a piano bench having the rigidity and strength of the ordinary bench and having detachable legs which can be separated from the rest 5 of the bench when it is desired to ship or store it. It is also an object of the invention to provide legs which will be so rigidly secured to the remainder of the bench that there will be no vibration in sympathy with the tones 10 of the instrument with which it is used. The bench embodying my invention also has the further advantage that the legs can be contained within the seat portion of the bench for shipment and can be assembled or disassembled quickly without the use of any tools. 15

The invention will be fully understood from the following description when taken in connection with the accompanying drawings and the novel features thereof will be 20 pointed out and clearly defined in the claims at the close of this specification.

Fig. 1 is a top plan view of a piano bench embodying my invention, a portion of the cover or seat member being cut away to show 25 the interior construction.

Fig. 2 is a transverse section of the bench shown in Fig. 1.

Fig. 3 shows one of the legs detached.

Fig. 4 is a section on line 4-4, Fig. 5, and

Fig. 5 is a section on line 5-5, Fig. 4, showing the mode of attaching the legs to the body portion of the bench.

Fig. 6 shows the bench with the cover or seat member partly broken away and the legs placed within the body of the seat portion, this being the position which they occupy when the bench is stored or shipped.

Referring to the drawings, at 11 is shown a cover or seat member hinged at 12 to the body or box portion and provided with an arm 13 to support the cover when in open position. The body portion 14 is box-like and is constructed with four sides 17, four corner members 15 and bottom 16. The corner members 40 are preferably mortised to the sides 17 so that with the cover 11 the whole forms a strong, rigid box.

Each corner member 15 is provided with a mortise or dowel hole 18 which is preferably 45 cylindrical and each leg 19 is provided with a tenon 20, to fit the mortise or dowel hole. The tenon 20 is preferably integral with the leg 19 and is formed with an annular groove 21 and provided at its top with a cushion

member or buffer 22. The tenon 20 and 55 cushion member 22 is longer than the mortise 18, so that when the shoulder 23 of the leg is against the under side of the corner member, the cushion 22 will be above the top surface of the box portion of the bench. 60 There is also provided on the shoulder 23 of the leg a pin 24 which engages a slot 25 (see Figs. 4 and 5). This pin and slot prevent 65 axial displacement of the leg 19 with relation to the corner post 15 and line up the edges of the leg and the corner post.

The corner posts are each provided with horizontal holes 26, 26 leading from the interior of the box portion, these holes being tangent to the annular groove 21 in the tenon 70 20 when the tenon is in place in the corner member 15. These holes 26, 26 receive the two legs of a staple 27. The staple 27 can be inserted and withdrawn only from the inside of the box portion of the seat and 75 therefore is entirely concealed from view. It locks the tenon of the leg against lengthwise movement so that it cannot be withdrawn or drop out while the staple is in place. In practice when it is desired to knock 80 down the bench for storage or shipment, the staples are easily pulled out, and the tenon is then withdrawn from its mortise.

As already stated, there is placed on the top of the tenon portion 20 of each leg a cushion member 22 and the tenon is made of such length that the cushion member projects above the top surface of the corner members 15 when the legs are in place. Therefore, when the seat portion or cover 11 is 85 closed, it rests on the cushion members and the load is transmitted chiefly and directly through the tenon 20 and leg 19 to the floor. As a result of this construction, the box member is relieved of the load imposed on the 90 bench by the weight of the occupant.

I find in practice that it is possible to make a good fit between the tenon on the leg member and the mortise in the corner member and that a bench constructed as described is 95 as firm and rigid as a bench of the same material having integral legs.

While I have shown and described the use of a cylindrical tenon and a corresponding mortise and a pin and slot as means for preventing the rotation of the leg relatively to the corner member, I do not intend to limit myself to this or other details except as spe-

cifically stated in the claims appended hereto.

What I claim is:

1. An improved piano bench comprising a seat portion and a body portion with mortises therein, legs having tenons to be received within the mortises, said tenons being longer than the length of the mortises, and there being means to prevent the rotation of each leg and to prevent movement longitudinally. 40
10. 2. An improved piano bench comprising a box portion provided with corner members having mortises therein, detachable legs having tenons received within and projecting above the mortises, there being a recess in the tenon, and a locking member passing through the corner member and engaging the recess in the tenon. 50
20. 3. An improved piano bench having a body portion with cylindrical mortises therein, detachable legs having cylindrical tenons received within the said mortises, an annular recess formed in the tenon and a locking member passing through the body portion from the interior thereof and engaging the annular recess to prevent longitudinal movement of the leg, and means for preventing the rotation of the leg about the tenon as an axis. 55
30. 4. An improved piano bench having a body portion with mortises therein, detachable legs for supporting the body portion, each leg having a tenon of greater length than the mortise and extending therethrough, and a cover for the body portion resting on the ends of the tenons which protrude above the level 60 of the body portion. 65
35. 5. An improved piano bench comprising a body portion having corner members at each corner, each corner member having a vertical cylindrical mortise therein, detachable legs having a cylindrical tenon and a shoulder formed in the upper end thereof, said tenon being longer than the length of the mortise and a cover for the box member adapted to rest on the protruding upper ends of the tenons when the legs are in place. 45
40. 6. An improved piano bench comprising a body portion having corner members at each corner, each corner member having a vertical cylindrical mortise therein, detachable legs having a cylindrical tenon and a shoulder formed on the upper end thereof, said tenon being longer than the length of the mortise and a cover for the box member adapted to rest on the protruding upper ends of the tenons when the legs are in place, and means 50 for locking the legs against axial and circumferential displacement. 55
50. 7. An improved piano bench comprising a body portion having corner members at each corner, each corner member having a vertical cylindrical mortise therein, detachable legs having a cylindrical tenon and a shoulder formed in the upper end thereof, said tenon being longer than the length of the mortise, a cover for the box member adapted to rest 60 on the protruding upper ends of the tenons when the legs are in place, and cushion members interposed between the ends of the tenons and the seat member. 65

In testimony whereof I affix my signature.

CLARENCE H. POND.
